UNITED STATES PATENT OFFICE.

KEIICHI SEO, OF KANAGAWA-KEN, JAPAN.

PROCESS OF CLARIFYING SUGAR SOLUTIONS.

No Drawing. Application filed November 28, 1923, Serial No. 677,524, and in Japan November 30, 1922.

This invention relates to a process of clarifying sugar solution, which consists in adding to sugar solution (molasses, cane sugar juice, sugar beet juice, impure starch sugar solution and "ame" thereof (a kind of sticky syrup)) a solvent of fatty substance immiscible with water and lighter than it; or in adding to the above solvent any water-soluble metallic compounds except alkali-metals, or in adding the solvent of fatty substance to the sugar solution after having acidified the latter with organic or inorganic acid and agitating the mixture and allowing it to settle; the impure matters rising to the surface of the water solution in a gel-form or dissolving in the solvent of fatty substance, and then removing the same.

The object of the present invention is to remove impure matters and bad odor from sugar solution by a simple method, thus facilitating decolorization, filtration, evaporation and crystallization. Sugar solution (molasses, cane sugar juice, sugar beet juice, impure starch sugar solution or "ame" thereof) contains a large quantity of impure matters, the large part of which consists of such viscid substances as pectine, gummy substances, albuminoid substance, etc. Though the quantity of such viscid substances varies according to the kind of sugar solution, the largest quantity is found in molasses, which contains about 7 to 16% of them, and these do not precipitate perfectly with the clarifying agent now used in sugar refining work. Besides the above substances, the sugar solution contains proteins and derivatives thereof, fatty oils, resins, alkaloids, organic acids and coloring matter being dissolved colloidally; such sugar solution has a bad taste and odor and is viscid, which prevents decolorization, filtration, evaporation and crystallization in a great degree.

This invention consists in coagulating perfectly the colloids suspending in sugar solution, and thus precipitating impure matters contained in the solution.

The following is the manner of carrying this invention into effect.

In case the sugar solution is molasses, use it as it is, or if it is too thick, add water to a suitable degree. In case of cane sugar juice and sugar beet juice, use them as they are or mix with them any metallic hydroxides except alkali-metals. The starch sugar solution producing by saccharifying impure

starch with acid and "ame" thereof may be used are they are. Add to the sugar solution one fifth part or equal quantity of a solvent immiscible with water and lighter than it (naphtha petroleum, benzin, petroleum benzin, petroleum ether, or the like). After shaking and stirring the mixture violently, allow the same to settle; until the colloidal substance rises to the surface of water solution in a gel-form. In this process almost all the metallic compounds contained in the solution (except alkali-metals) combine with colloidal substance and float up on the surface of water solution. The objectionable odor of fatty oil, resin and alkaloid, can be removed by dissolving in the solvent and then settling or decanting them. However, in case it is impossible to remove impure matters entirely by the above method according to some kind of sugar solution, use the solvent together with water-soluble metallic compounds except alkali-metals (mostly salts of calcium, iron, copper and lead groups are used), or add the solvent to sugar solution after acidifying the latter with inorganic or organic acid, and after shaking and stirring the same violently, allow it to settle until the impure matters rise to the surface of the solution in a gel-form or are dissolved in the solvent. In this process, the metallic compound combines with colloidal substances chemically, its quantity must be equivalent to the impurity contained in sugar solution. The impure matters thus separated are removed by means of decantation or filtration. The quantity and kind of the chemicals used in removing the said impure matters differ according to the kind of sugar solution and of goods to be manufactured. The remaining chemicals are removed by evaporation or precipitation by proper means. By this simple method all impure matters can be almost entirely removed from sugar solution. Molasses so treated loses its odor and becomes palatable, and increases its pure sugar content by 20 to 36%. By this method, we can economize the labor of refining sugar solutions and increase considerably the percentage of crystallizable sugar. Moreover, in impure starch solution and "ame" thereof, the quality of manufactures is improved, and goods of superior quality may be made out of such impure starch.

"Ame" is an edible syrup used in Japan

2
and consists essentially of starch saccharified by green malt.

Claims:

1. The herein described process of clarifying sugar solution, which consists in acidifying the sugar solution; then adding to the sugar solution a solvent of fatty substances immiscible with and lighter than water; agitating the mixture; and then permitting the mixture to settle, the impure matters rising and floating upon the surface of the mixture in a gel-form.
2. A process of clarifying sugar solution, which consists in adding to sugar solution a solvent of fatty substance immiscible with and lighter than water; and a water-soluble non-alkali metallic compound; agitating the

mixture and allowing same to settle, the impure matters floating upon the surface of water and partly dissolved in the solvent of fatty substance; and finally removing the same by decantation or filtration.

3. A process of clarifying sugar solution, which consists in acidifying a sugar solution, adding thereto a solvent of fatty substance immiscible with and lighter than water; agitating the mixture; allowing it to settle until the impure matters rise to the surface of the mixture, and finally removing the impure matters.

In testimony whereof I have affixed my signature.
